BOOK COVER

Erwin Wolberg, New York, N. Y., assignor to Wolberg-Sims Printing & Engraving Co., New York, N. Y., a partnership

Application December 24, 1956, Serial No. 44,313

Term of patent 3½ years

(Cl. D6—2)

The figure on the drawing is a top plan view of a book cover showing my new design.

The inner faces of the book cover are plain and unornamented and the essential features of the design reside in the portions shown in solid lines on the drawing.

I claim:

The ornamental design for a book cover, substantially as shown and described.
